UNITED STATES PATENT OFFICE.

AMOS S. STETSON, OF SOUTH ABINGTON, MASSACHUSETTS.

HYDROCARBON-ENGINE.

SPECIFICATION forming part of Letters Patent No. 267,946, dated November 21, 1882.

Application filed August 28, 1882. (No model.)

To all whom it may concern:

Be it known that I, AMOS S. STETSON, a citizen of the United States, residing at South Abington, in the county of Plymouth and Commonwealth of Massachusetts, have invented a new and useful Improvement in Hydrocarbon-Engines, of which the following is a specification.

My invention relates to the lubrication and cooling of the cylinder and piston, and to the utilizing for such lubrication of a certain substance resulting from the combustion of petroleum or its products, which has hitherto, by reason of the continuous and excessive heat in the cylinder, accumulated therein in the form of a charred scale or ash, preventing the perfect working of the parts and necessitating frequent stops for cleaning. Formerly this residue of combustion would adhere to the sides of the cylinder and on the piston, and by reason of the continuous heat bake into a scale so hard that it could only be removed by a chisel or file, and this trouble could not be obviated by adding lubricant from without, which rather increased the difficulty; but this hitherto injurious residue my invention converts by condensation into a superior lubricant, and a hydrocarbon-engine employing my combination furnishes its own lubricant at every stroke of the piston. I attain these objects by the mechanism illustrated in the accompanying drawings, in which—

Figure 1 is a longitudinal section of a horizontal cylinder and piston embodying a portion of my invention. Fig. 2 is a longitudinal section of the same at right angles to Fig. 1, and showing also the flexible tube forming part of the combination which I desire to secure by Letters Patent; and Fig. 3 is a section of the piston-head, showing the manner of the water-circulation through the same.

Similar letters refer to similar parts throughout the several views.

A A are the longitudinal sides of the cylinder, which, for reasons hereinafter more fully set forth, is preferably of a length nearly twice that of the working stroke of the piston.

B B is the working cylinder head, or "fire-

head," (between which and F the impelling fluid is introduced.)

50

K is the cross-head.

H is the water-jacket inclosing the cylinder.

C is the water-head.

F is the piston-head.

D is a hollow rod through which the water 55 is conducted to the piston-head.

E is the hollow rod by which water is conducted from the piston-head.

L L is a flexible tube carrying the water from the discharging-rod of the piston into the wa- 60 ter-jacket.

My invention having no relation to the method of driving the piston, no supply or exhaust mechanism is shown.

The working of my invention is as follows: 65 Water is forced by any suitable means through the hollow piston-rod D, whence, following a course indicated in Fig. 3, it passes through the cylinder-head F, through the hollow piston-rod E, thence through a flexible tube, L, 70 into the cylinder-head B, thence through the water-jacket H of the cylinder into the water-head C, and thence to waste.

By making the cylinder of a length equal to, say, twice that of the working stroke of the 75 piston, the half of the cylinder next the water-head C is kept perpetually cool, and by extending the surface of the piston-head by the trunk G a larger area is presented to the influence of the cool end of the cylinder. The 80 result is that the piston-head is maintained sufficiently cool, so that the products of combustion in the cylinder, which in continued heat would, as before described, become a scale or ash, are by the cooled piston, on its return- 85 stroke, condensed into a superior lubricant, and the piston and cylinder, instead of clogging, become self-lubricating.

I am aware that hollow piston-rods, hollow pistons, flexible tubes for supplying water to 90 the same, and water-jackets have been heretofore known and used, and in various combinations.

What I claim, and desire to secure by Letters Patent, is—

In a hydrocarbon-motor, a cylinder pro-

95

longed beyond the working stroke of the piston sufficiently to prevent the combustion against the working-face of such piston from directly heating that portion of the cylinder
5 beyond such working stroke, in combination with a trunk-piston so extended as to present a designedly large surface to such prolonged

and unheated portion of such cylinder, and a water-circulation, substantially as shown and described.

AMOS S. STETSON.
